DISPLAY DEVICE

Herman H. Hutt, Brooklyn, N. Y.

Application July 1, 1948, Serial No. 36,332

4 Claims. (Cl. 40—124.1)

1

This invention relates to display devices adapted to produce an extended or protruding display, preferably in translucent or transparent material. Still more particularly, the invention deals with devices of this kind wherein the display is normally arranged in a flat coupled relationship, facilitating shipment or transportation and compact packaging and whereby the display may be quickly and easily set up for use by simply pushing one edge portion of the display in the direction of the opposed end portion, in which operation, the coupled parts slide one upon the other and the front wall portion is bulged or extended to predetermined form.

The novel features of the invention will be best understood from the following descriptions when taken together with the accompanying drawing, in which certain embodiments of the invention are disclosed, and in which the separate parts are designated by suitable reference characters in each of the views; and in which:

Fig. 1 is a perspective view of a display made according to my invention, showing the same in its set up display position.

Fig. 2 is a rear view of the device as seen in Fig. 1, showing the same in the flat or folded position in dot and dash lines.

Fig. 3 is a section on the line 3—3 of Fig. 1, showing the method of initially assembling the parts preparatory to packaging and later displaying the same.

Fig. 4 is a section on the line 4—4 of Fig. 2.

Fig. 5 is a sectional plan view of a modified form of construction which I employ.

Fig. 6 is a view similar to Fig. 5, showing another form of construction; and

Fig. 7 is a section on the line 7—7 of Fig. 5.

In the construction shown in Figs. 1 to 4 inclusive, I provide a display device comprising a back-board or sheet 10 of relatively firm or rigid material, such as heavy cardboard, fibreboard or the like. At 11, I have shown a flexible and preferably transparent or translucent display sheet which can be characterized in any desired manner for advertising or display purposes. For example, at 12, in Fig. 1, is diagrammatically illustrated a display printed or otherwise formed on the sheet 11, and at 12' is diagrammatically illustrated the shadow of the display as it would appear on the front face of the back-board or sheet 10.

One side edge portion of the sheet 11 is folded, as seen at 13, note Fig. 3, and a flanged edge 14 is arranged upon and secured to the rear surface of the sheet 10. The other side edge portion of

2

the sheet 11 is folded, as seen at 15, and has a flanged portion 16 secured to the rear surface of what I term a lock or supporting element 17. The element 17 comprises two parts 18 and 19 scored for relative folding one with respect to the other, as indicated at 20. The part 18 is of a height equal to the height of the sheet or board 10, note Fig. 2. Whereas, the part 19 is of considerably less height and is disposed centrally of the part 18 and may be characterized as a locking and coupling tongue.

The tongue 19 is adapted to be passed frictionally beneath a retaining strap or bar 21, the bar having inturned upper and lower ends or flaps 22 and 23, note Fig. 4, these ends being secured to the inner surface of the bar 21 and to the rear surface of the sheet 10, so as to form an elongated slot or opening 24 into and through which the tongue 19 is adapted to pass. The inner ends 22' and 23' of the flaps 22 and 23 form guides through which the upper and lower edges of the tongue 19 snugly, but freely pass, thus maintaining alinement of the parts one with respect to the other, particularly if the device is hung from a support which may pass through an opening 25 in the back wall 10.

When the parts are assembled and set up for display use, as seen in Fig. 1, and in full lines in Fig. 2, the inner end or edge of the part 18 abuts against the flaps 22 and 23 and the tongue 19 protrudes well beyond the strap or retaining bar 21. However, when the sheet 11 is brought flatly upon the sheet or back wall 10, in the compact or full folded position of the parts, the tongue 19 will still remain in the aperture 24 of the strap, as is clearly indicated in dot and dash lines in Fig. 2. By providing the fold 20 between the parts 18 and 19, initial assemblage of the device is made possible. In other words, the parts can be folded to the position indicated in Fig. 3 to enable the free edge of the tongue 19 to be inserted into the aperture 24. However, when once inserted, and the parts 18 and 19 are brought into alinement, they are retained in this position at all times. When the device is delivered to a customer or prospective user, it is in the flat state, indicated in dot and dash lines in Fig. 2, and to assemble the device for display use, all that the individual has to do, is to push inwardly on the folded edge 15 to advance the tongue 19 to the full line position of Fig. 2, which automatically bows or extends the flexible sheet 11 to the curved position, clearly illustrated in Fig. 1.

55 By reason of the frictional engagement be-

tween the tongue 19 and the strap 21 and rear surface of the back-board or sheet 10, the parts are retained in the set up position as shown in Fig. 1, but can be forcefully extended to the collapsed position. This latter is possible by having the flaps 22 at substantially the same thickness as the tongue 19, or slightly thinner so that the tongue 19 can be frictionally passed through the opening 24. It will be understood that both parts 18 and 19 rest flatly and snugly upon the rear surface of the sheet 10, particularly when the device is in set up condition.

In Figs. 5 and 7 of the drawing, I have shown a slight modification wherein a back sheet 26, generally similar to the sheet 10 is employed, a front flexible sheet 27, similar to the sheet 11 and a lock element 28, similar to the element 17 operating in connection with a strap or bar 29, similar to the bar 21.

In Figs. 5 and 7, the upper and lower edges of the sheet 26 have foldable triangular members 30 and 31 which are adapted to be extended into the sheet 27 to support said sheet to produce the resulting triangular cross-sectional form illustrated in Fig. 5. In other words, the members 30 and 31 can be of different shapes and forms and serve to give predetermined contour to the flexible and forwardly extended sheet 27.

In Fig. 6 of the drawing, I have shown another modification in which the entire display device is made from a single sheet of relatively rigid or firm material, the sheet being folded to form a back wall 32, a bevelled side wall 33, a front wall 34, another bevelled side wall 35 and a lock element 36, the latter being similar in all respects to the lock element 17 and operating in conjunction with a strap or bar 37, similar to the bar 21 and secured to the rear surface of the back sheet 32. With this type of construction, the tongue portion 38 of the lock element 36 will be made sufficiently long to compensate for the flat positioning of the wall parts 33, 34 and 35 to maintain the interengaged assemblage, as indicated in dot and dash lines in Fig. 2 of the device, when the device is fully collapsed. With the structure shown in Fig. 6, the unitary frame may be composed of cardboard or fibreboard, which would produce an opaque display visible only on the external surfaces of the walls 33, 34 and 35. Whereas, in the structure shown in the other figures, the outwardly extending wall can be formed from the transparent or translucent material, so that three-dimensional effects can be obtained in the characterization of the display by virtue of the shadows thrown upon the surface of the back wall or panel of the device.

By reason of the method of construction, a very attractive display of the type and kind under consideration can be produced at a relatively nominal cost and the displays can be conveniently handled from a standpoint of packaging and shipment and/or storage, and at the same time, quickly and easily set up without performance of any type or kind of folding, bending, twisting or other operations. Extended devices, of the kind under consideration, become self-supporting on a counter, table, floor or other support, and at the same time, can be hung from a suspending hook or nail.

Having fully described my invention, what I claim as new and desire to secure by Letters Patent is:

1. A display device of the class described comprising a back-board of relatively firm material, a sheet of flexible translucent material of greater

width than said back-board, one edge of the last named sheet being foldably hinged to one side edge portion of said back-board, the other side edge portion of said flexible sheet being foldably attached to a lock element, a strap arranged vertically on the back-board and forming, in conjunction therewith, a pocket for reception of said lock element, said lock element retaining the parts in assembled relationship at all times while permitting movement of the parts from a flat collapsed position to a position in which the flexible sheet is extended forwardly with respect to and within side edges of said back-board, said lock element comprising hingedly related parts, one part comprising a tongue member slidably and frictionally engaging said strap and back board, and the other part being of substantially the same vertical dimensions as that of the back-board and abutting the strap in the support of said parts in set up condition one with respect to the other.

2. A display device of the class described comprising a back-board of relatively firm material, a sheet of flexible translucent material of greater width than said back board, one edge of the last named sheet being foldably hinged to one side edge portion of said back-board, the other side edge portion of said flexible sheet being foldably attached to a lock element, a strap arranged vertically on the back-board and forming, in conjunction therewith, a pocket for reception of said lock element, said lock element retaining the parts in assembled relationship at all times while permitting movement of the parts from a flat collapsed position to a position in which the flexible sheet is extended forwardly with respect to and within side edges of said back-board, said lock element comprising hingedly related parts, one part comprising a tongue member slidably and frictionally engaging said strap and back board, the other part being of substantially the same vertical dimensions as that of the back-board and abutting the strap in the support of said parts in set up condition one with respect to the other.

3. A display device of the character described, comprising relatively foldable parts, one part comprising a back wall defining the width of the display, said part having a retaining strap forming on the rear surface thereof a pocket, another front part of greater width than the back part and foldable with one side thereof, said front part having throughout the length of the free side edge thereof a foldable portion comprising a lock element, said lock element having a reduced tongue arranged in said pocket and frictionally engaging said strap and back wall in supporting the front part in outwardly extending position within side boundaries of the back part, and said tongue being retained in engagement with the strap when the parts are collapsed flatly one upon the other.

4. A display device of the character described, comprising relatively foldable parts, one part comprising a back wall defining the width of the display, said part having a retaining strap forming on the rear surface thereof a pocket, another front part of greater width than the back part and foldable with one side thereof, said front part having throughout the length of the

free side edge thereof a foldable portion comprising a lock element, said lock element having a reduced tongue arranged in said pocket and frictionally engaging said strap and back wall in supporting the front part in outwardly extending position within side boundaries of the back part, said tongue being retained in engagement with the strap when the parts are collapsed flatly one upon the other, and means on the back wall part cooperating with the front part for retaining said last named part in predetermined cross-sectional contour when the front part is in extended position.
